COMBINED LUGGAGE AND CHILD CART FOR TRANSPORTATION TERMINALS

James R. Hughes, Sedalia, Colo., assignor to J. R. H. Corporation, Sedalia, Colo., a corporation of Colorado

Filed Oct. 20, 1965, Ser. No. 87,630

Term of patent 14 years

(Cl. D14—3)

FIG. 1 is a perspective view of a combined luggage and child cart for transportation terminals embodying my new design;

FIG. 2 is a side elevational view of the cart of FIG. 1;

FIG. 3 is a front elevational view of the cart of FIG. 1; and

FIG. 4 is a top plan view of the cart of FIG. 1.

I claim:

The ornamental design for a combined luggage and child cart for transportation terminals, substantially as shown and described.
